UNITED STATES PATENT OFFICE.

EDGAR D. CHURCH, OF SAGINAW, MICHIGAN, ASSIGNOR TO JACKSON & CHURCH COMPANY, OF SAGINAW, MICHIGAN, A CORPORATION OF MICHIGAN.

AUTOMATIC FEEDER FOR JOINTERS.

Application filed July 24, 1922. Serial No. 577,133.

To all whom it may concern:

Be it known that I, EDGAR D. CHURCH, a citizen of the United States of America, residing at Saginaw, in the county of Saginaw and State of Michigan, have invented certain new and useful Improvements in Automatic Feeders for Jointers, of which the following is a specification, reference being had therein to the accompanying drawings.

This invention relates to wood planing machines and particularly to that type known as jointers which are designed to form a true surface on the work.

An object of the invention is to provide simple and effective means for advancing the work to the planing cutter while at the same time holding the work in a fixed plane and avoiding any pressure on the work sufficient to spring the same and which would result in subsequent distortion.

Another object is to provide a series of strong and durable fingers which have a plurality of points arranged in a circular arc at the ends thereof for facilitating engagement with the work.

Another object is to provide a series of fingers which may be easily and readily inverted so as to prolong the life thereof.

Another object is to provide an efficient and practical device which is simple in construction and which can be manufactured at a very low cost.

With the above and other objects in view the invention consists in certain novel features of construction, combination and arrangement of parts as will be more fully described and particularly pointed out in the appended claims.

In the accompanying drawings:

Figure 1 is a side elevation of a portion of a jointer to which my improvement is applied;

Figure 2 is a cross-section showing one of the cross-bars of the holder and feeder in elevation;

Figure 3 is a plan view of Figure 2;

Figure 4 is a detail sectional view taken on the line 4—4 of Figure 3;

Figure 5 is a detail perspective view of one of the fingers;

Figure 6 is a detail sectional view taken on the line 6—6 of Figure 4.

Referring now to the drawings in which like characters of reference designate corre-

sponding parts throughout the several views, the numeral 1 designates the bed or table of the jointer over which the work is fed to the planing cutter 2. A plurality of vertically adjustable standards 3 extend above the table and are secured to a frame 4 which supports the feeder.

The feeder includes an endless carrier having a plurality of spaced bars 5 secured to an endless chain 6 which is trained around sprocket wheels 7. Any suitable means may be employed for driving either one of the sprocket wheels to actuate the endless carrier. A plurality of bars 8 are arranged above the bars 5 and are parallel thereto. The bars 5 and 8 are spaced apart by means of the tubular spacers 9 and are secured to each other by means of bolts or rivets 10 extending through the spacers. The bars 5 and 8 have aligned openings 75 therein, preferably of polygonal form for engaging correspondingly shaped fingers 11 which engage the work. The opposite ends of each finger are provided with a plurality of spaced transversely extending points 12 80 which are arranged in a circular arc to facilitate engagement with the work. The fingers are provided intermediate their ends with cross bores 13 and 14 which are spaced a predetermined distance from the ends of 85 the fingers. Split keys 16 are normally inserted in the bores 14 and engage the bars 5, the bores 13 being used only when the fingers are inverted. Coil springs 17 are sleeved upon the fingers intermediate the bars 5 and 8, the upper ends of said springs 90 abutting against the bars 8 while the lower ends thereof engage the split keys 16.

With the construction as described it is only necessary to withdraw the split keys 95 to remove the fingers in case the points at one end thereof become worn or broken, or to replace a broken or defective spring. This operation and the operation of replacing the fingers will occupy only a short time, 100 so that replacement can be made without holding the machine out of work for any length of time.

What I claim as my invention is:

1. In a feeder for jointers, the combination with an endless carrier, of a series of fingers carried by said carrier having a plurality of points arranged in a circular arc for engagement with the work.
2. In a feeder for jointers, the combination with an endless carrier, of a series of fingers carried by said carrier having a plurality of points arranged in a circular arc for engagement with the work.

tion with an endless carrier, of a series of fingers carried by said carrier having a plurality of spaced parallel transversely extending points for engagement with the 5 work.

3. In a feeder for jointers, the combination with an endless carrier, of a series of fingers carried by said carrier having a plurality of transversely extending points 10 for engagement with the work, certain of said points being shorter than the others.

4. In a feeder for jointers, the combination with an endless carrier, of a series of fingers carried by said carrier having a plurality of points for engagement with the 15 work, the points at the sides of said fingers being shorter than the intermediate points.

5. In a feeder for jointers, the combination with an endless carrier, of a series of 20 cross bars therefor, a series of spring pressed pins slidably engaging said cross bars and yieldably pressed towards the work, each of said pins being formed with a plurality of points at its lower end arranged in the arc 25 of a circle to facilitate engagement with the work.

6. In a feeder for jointers, the combination with an endless carrier including a series of cross-bars, a series of fingers carried 30 by said bars and having points at one end thereof for engagement with the work, and means engaging one portion of said fingers and normally in engagement with said bars for limiting the downward movement of 35 said fingers, said fingers, being invertible and having points at the opposite end thereof for engagement with the work, the means aforesaid being adapted to engage said bars, and another portion of said fingers when the 40 latter are inverted to limit the downward movement thereof.

7. In a feeder for jointers, the combination with an endless carrier including a series of cross-bars, a series of fingers carried 45 by said bars and having points at one end thereof for engagement with the work, said fingers having spaced openings therethrough, means engageable with one of the openings 50 in said fingers and normally in engagement with said bars for limiting the downward

movement of said fingers, said fingers being invertible and having points at the opposite ends thereof for engagement with the work, the means aforesaid being adapted to engage said bars and the other of said openings in 55 said fingers when the latter are inverted to limit the downward movement thereof.

8. In a feeder for jointers, the combination with an endless carrier including a series of cross-bars, a series of bars arranged parallel 60 to and spaced from said bars, fingers extending through said parallel bars and having points at one end thereof for engagement with the work, removable means engaging one portion of said fingers and 65 adapted to engage the bars of one series to limit the downward movement of said fingers, and yieldable means engaging said fingers and said removable means for normally retaining the latter in engagement with 70 the bars of one series.

9. In a feeder for jointers, the combination with an endless carrier including a series of cross-bars, a series of bars arranged parallel to and spaced from said bars, fingers extending through said parallel bars and having points at one end thereof for engagement with the work, removable means 75 engaging one portion of said fingers and adapted to engage the bars of one series to 80 limit the downward movement of said fingers, yieldable means engaging said fingers and said removable means for normally retaining the latter in engagement with the bars of one series, said fingers being adapted 85 to be inverted and having points at the opposite end thereof for engagement with the work, the removable means aforesaid being adapted to engage the bars of said series and another portion of said fingers to limit 90 the downward movement thereof when inverted, and the yieldable means aforesaid being adapted to engage said fingers and said removable means when said fingers are inverted to normally retain said removable 95 means in engagement with the bars of one series.

In testimony whereof I affix my signature.

EDGAR D. CHURCH.
